UNITED STATES PATENT OFFICE.

OTTIS F. MEADOWS, OF ASHEVILLE, NORTH CAROLINA.

ADVERTISING DEVICE.

Application filed September 21, 1926. Serial No. 136,833.

- This invention relates to a motor vehicle designed primarily for advertising cigars and other articles from which smoke is emitted while in use.
- 5 One of the objects of the invention is to provide a means for exhausting the gases from the exhaust manifold of the engine of the vehicle into an article carried by the vehicle from which the exhaust gases or smoke 10 will be discharged, thereby to constitute an attractive advertising medium.

Another object is to provide a means for removing condensed moisture, in the form of unconsumed fuel, oils, etc. from the article 15 into which the gases are exhausted so that there will be no danger of liquid matter being blown from the advertising article and falling upon passers-by.

With the foregoing and other objects in view which will appear as the description proceeds, the invention resides in the combination and arrangement of parts and in the details of construction hereinafter described and claimed, it being understood that changes 25 in the precise embodiment of the invention herein disclosed may be made within the scope of what is claimed, without departing from the spirit of the invention.

In the accompanying drawings the preferred form of the invention has been shown.

In said drawings,

Figure 1 is a side elevation of a portion of a motor vehicle having the present improvements combined therewith.

35 Figure 2 is a rear elevation thereof.

Figure 3 is a section through the casing.

Referring to the figures by characters of reference 1 designates a motor vehicle which can be provided with any suitable type of 40 delivery body 2. At any preferred point on this body is mounted a large representation of the article being advertised. In the present instance there has been shown the repre-

sentation of a cigar, the same being indicated at 3. This cigar is formed of a hollow casing properly shaped, the rear end thereof being formed with a vent opening 4 which can be partly closed with wire netting 5 if so desired. Opening into the rear portion of this casing is a pipe 6 leading from the muffler 7 into which gases are exhausted from the engine of the vehicle. A drain pipe 8 extends downwardly from the lowest portion of the casing to a point below the body 2.

In practice the exhaust gases from the engine of the vehicle are directed into the casing 3 and will issue from the opening 4 so as to give the article the appearance of a smoking cigar. Any unconsumed fuel or oils carried to the casing 3 with the exhausting gases 55 will not be expelled from the casing with the gases but will condense and flow downwardly through the vent pipe 8 to the street. Consequently the vehicle will be kept free of stains from oils, etc. which might otherwise be delivered through the open end 4 and all danger of spattering pedestrians with particles of oil 65 is likewise eliminated.

What is claimed is:

The combination with a motor propelled vehicle including a body, of a hollow casing mounted on the body simulating an article being advertised, said casing having an outlet opening from which the bottom portion of the casing is inclined downwardly, a screen 75 extending across the outlet opening, means for directing exhaust gases to the casing from the engine of the vehicle, and a drain pipe extending from the lowest portion of said casing downwardly to a point below the body of 80 the vehicle for delivering accumulated oil and the like onto the ground.

In testimony that I claim the foregoing as my own, I have hereto affixed my signature.

OTTIS F. MEADOWS.
